UNITED STATES PATENT OFFICE.

REUBEN HALEY, OF BEAVER, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A NECK AND STOPPER FOR GLASS ARTICLES.

43,039.

Specification for Design.

Patented Sept. 24, 1912.

Application filed July 22, 1912. Serial No. 710,984. Term of patent 7 years.

To all whom it may concern:

Be it known that I, REUBEN HALEY, a citizen of the United States, and residing at Beaver, in the county of Beaver and State of Pennsylvania, have invented a certain new, original, and ornamental Design for a Neck and Stopper for Glass Articles, shown in the accompanying drawing, which is a view in perspective of the same.

I claim:—

The ornamental design for a neck and stopper for glass articles, as shown.

REUBEN HALEY.

Witnesses:

JOHN BIGHAM,
WILLIAM R. NICKEL.
